Application February 26, 1941, Serial No. 330,703
In Canada March 27, 1940

11 Claims. (Cl. 83—10)

This invention relates to improvements in gyratory crushers of the type set forth in my original application Serial No. 282,227, filed June 20, 1939; the present application being a continuation, in part, of said original application.

In its preferred embodiment my improved crusher comprises a frame, an outer annular crushing member of substantially conical form mounted on said frame so that its central axis is vertical, an inner annular crushing member of substantially conical form located within said outer member, a support on which the inner member is rotatably supported in a tilted position so that the central axis of said inner member is inclined to intersect the central axis of the outer member at a focal point located below said inner member and means for gyrating the inner member so that its central axis describes an inverted cone having its apex at said focal point. This type of crusher is distinguished by a novel crushing action in that the portion of the inner member which is making a crushing stroke in the direction of the outer member approaches said outer member with substantial downward component of motion. Under these circumstances the crushable material interposed between the two crushing members is subjected to torsional, shearing, and bending forces which enable the crusher to perform an exceptionally high ratio of reduction on said material in one pass through the crushing zone. Reduction ratios as high as 1 to 36 and 1 to 48 have actually been obtained in practice with crushers designed in accordance with this invention. These high reduction ratios are made possible by designing the crusher so that, during a crushing stroke of the inner member, the downward component of motion of said member, especially at the discharge end of the crushing zone, is suitably proportioned with respect to the crushing motion of said member in the direction of the outer member. When the crushing approach which the lowest crushing point on the inner member makes toward the outer member is suitably proportioned with reference to the downward motion of said point, it is possible to provide a crusher in which the crushing surfaces can be brought closer together with crushable material interposed between them than is the case with any of the crushers now on the market.

Owing to the exceptionally high ratio of reduction which it performs on crushable material on one pass through the crushing zone, my improved crusher makes it possible to dispense with considerable intermediate equipment commonly em-

ployed in rock crushing operations, such, for example, as the shaker screens, crushing rolls, ball mills, conveyors and dust fans.

A further advantage of my improved crusher is that it lends itself to the use of anti-friction bearings for mounting all rotating parts so that the power required to operate the crusher is considerably reduced as compared with prevailing standards.

10 A further feature resides in the provision of simple and efficient means for adjusting the relative setting of the outer and inner crushing elements to produce a crushed product of the desired degree of fineness.

15 A further feature resides in the provision of novel means whereby dust and foreign material are excluded from said adjusting means without resorting to the use of fabricated rings, channels, cylindrical dust shields and other similar accessories which have heretofore been employed for this purpose.

20 A still further feature resides in the provision of novel means whereby an efficient oil seal is provided between the interior load bearing and lubricated surfaces of the crusher and the exterior dust bearing air and mechanism.

25 A further feature of the invention resides in the provision of adjusting means incorporated in the crusher for changing the obliquity of the gyrating axis of the inner crusher member with reference to the axis of the outer crushing member.

30 Another advantage of the unique crushing action of my improved crusher is that it eliminates attrition and thereby materially reduces the wear on the crushing surfaces.

35 Proceeding now to a more detailed description of the invention reference will be had to the accompanying drawings, wherein—

40 Fig. 1 is a vertical sectional view of my complete crusher assembly.

45 Fig. 2 is a perspective view showing the threaded segments and clamping members employed for adjusting the mantle element of the crusher.

50 Fig. 3 is an enlarged fragmentary sectional view illustrating the mounting of the cone element and the shaft by which the cone element is gyrated with reference to the mantle element.

55 Fig. 4 is an enlarged fragmentary sectional view showing the mechanism provided for varying the obliquity of the gyrating axis of the cone element.

Fig. 5 is an enlarged fragmentary sectional view of a portion of the mechanism illustrated in Figures 1 and 3.

Fig. 6 is a view partly in side elevation and

partly in vertical section of the main shaft of the crusher.

Fig. 7 is a plan view of the shaft shown in Fig. 6.

Fig. 8 is a plan view of an adapter sleeve.

Fig. 9 is a vertical sectional view of the adapter sleeve shown in Fig. 8.

Fig. 10 is a plan view of a washer.

Fig. 11 is a vertical sectional view of the washer shown in Fig. 10.

Fig. 12 is a plan view of a nut employed for securing the adapter sleeve on the shaft.

Fig. 13 is a sectional view of the nut shown in Figure 12.

Figs. 14 and 17 are diagrammatic views illustrating the crushing action characteristic of my improved crusher.

Figures 15 and 16 are diagrammatic views illustrating the effect of varying the location of the focal point about which the cone element of the crusher is gyrated.

Referring more particularly to the drawings, 4 designates a cylindrical frame provided with a square base 5 which rests flatly on the foundation 6. A cylindrical sleeve 7 is centered and rigidly supported in the frame by means of radial webbing 8 and branch sections 9, the latter forming part of the countershaft housing hereinafter referred to.

A rotatable bevel gear hub 10 is positioned in sleeve 7 by anti-friction bearings 11 and 12.

The inner cone 11a of bearing 11 is a force fit on the lower end of hub 10 and bears against the hub flange 10a. The outer cone 11b of bearing 11 is a force fit in an opening 11c provided at the lower end of sleeve 7 and rests on the cylindrical extension 13 of a cover 14 closing said opening.

The inner cone 12a of bearing 12 is a force fit on the upper end of hub 10 and bears against the upper side of hub flange 15. The outer cone 12b of bearing 12 is a force fit in a seat ring 16 and bears against an inwardly directed flange 17 at the upper edge of said ring. A flange 18 projects outwardly from the lower portion of ring 16 and bears on a shoulder 19 of sleeve 7. Ring 16 is bolted in place as indicated at 20.

A bevel gear 21 is fastened to the underside of gear hub flange 15 by bolts 22. This gear meshes with a driving bevel pinion 23 fixed to the inner end of a countershaft 24. The countershaft is journalled in the countershaft housing 25 by means of anti-friction bearings 26 and 27. Housing 25 is fitted in the bore 23 of frame section 9 and is secured in place by bolts 23. The outer end of housing 25 is provided with a removable bearing cover 30 provided with a central opening through which the countershaft 24 extends, said opening being sealed by suitable sealing means 31.

A spiral gear 32 is fixed to countershaft 24 adjacent bearing 26. This gear meshes with a spiral gear 33 fixed to a shaft 34 which operates an oil pump (not shown). The discharge side of the pump is connected to a central vertical oil passage 35 formed in the bottom cover 14 of sleeve 7. The cover 14 is also provided with a horizontal oil passage 36 and an oil collecting sump 37. The oil which is delivered to sump 37 as hereinafter described is returned, through passage 38, to an oil tank (not shown) to which the suction side of the pump is connected.

Sleeve 7 supports a sphere head generally indicated at 40. This sphere head is formed with a downwardly facing shoulder 41 and a depend-

ing cylindrical extension 42. The extension 42 is force-fitted in the upper portion of sleeve 7 so that the shoulder 41 bears on the upper end of the sleeve and is bolted thereto as indicated at 41a. It will also be noted that the lower end of extension 42 bears against the flange 10 of seat ring 16 and assists in retaining said ring in place.

Sphere head 40 has two annular spherical surfaces 43 and 44 formed thereon so that both surfaces have a common focus or center but different radii. As clearly shown in the drawings the area of surface 44 is considerably greater than the area of surface 43 but the radius of surface 44 is less than that of surface 43. The two surfaces 43 and 44 are separated by a cylindrical portion 45 (see Fig. 5) on which an oil seal ring 48 is shrunk fitted. An annular channel 49 is formed in the sphere head between the spherical surface 44 and the annular portion 45 and serves as a collecting channel for oil draining from the surface 44. The oil collecting in channel 49 passes through drain holes 50 into the interior of sleeve 7.

The spherical surface 44 is interrupted by an annular oil groove 51 located substantially midway between the upper and lower edges of said surface. Adjacent the mouth of the groove the side walls thereof are curved as indicated at 51a (Fig. 5) so that oil supplied to said groove will be distributed, according to a well-known oil feed thrust principle, to form a lubricating film between the surface 44 and the opposing spherically curved surfaces 52 of the head liner 53 herein-after referred to. Oil under pressure is supplied to oil groove 51 through oil passages 35 and 39 of cover 14, oil passage 54 of sleeve 7, oil passage 55 of ring 16 and oil passage 56 of sphere head 40. Excess oil supplied to groove 51 is forced through fluid passages 58 and 58a, pipe 59, pressure relief valve 60 and pipe 61 to countershaft housing 23 and serves to lubricate the countershaft bearings 26 and 27 and the spiral gears 32 and 33. The relief valve 60 controls the oil pressure which is indicated on pressure gauge 62 connected to pipe 55.

The crushing head liner 53 is made of high grade bearing bronze or other suitable material and is mounted on the spherical surface 44 in oil film contact therewith. When the crusher is in operation this liner serves to distribute the enormous concentrated rock crushing forces over the large spherical surface 44. Liner 53 (see Fig. 3) is provided with a cylindrical portion 64 located between a flat top surface 65 and a bevelled outer side surface 66. The cylindrical portion 64 is force fitted in a cylindrical portion 67 of a substantially conical head carrier 68 so that the liner surfaces 65 and 66 are brought in flat contact with complementary flat and bevelled surfaces 69 and 70 of the carrier. Head carrier 68 is bolted to liner 53 as indicated at 71 and is provided with a skirt portion 12 having a spherically curved surface 72a which conforms to and is disposed in close proximity to the spherical curved surface 43 of sphere head 40. The inner side of skirt portion 72 is shaped so that it forms, in conjunction with the sphere head 40, a channel or recess 73 which accommodates the oil seal ring 48 with sufficient clearance to permit the liner and carrier elements of the crusher head assembly to be moved through a complete gyration or stroke without coming in contact with said ring.

A conical crushing head 14 of manganese steel or other wear resisting material is fitted on head

carrier 63 in machine ground matching contact therewith and is secured to the carrier by the head fastening screw 75. The head of screw 75 bears against the bottom wall of a recess 76 provided in the head 74. A rubber disc 77 is fitted in recess 76 to exclude dust and prevent abrasion of screw 75. The portion of the carrier into which screw 75 is threaded is extended in the form of a boss 78 (Figs. 1 and 3) which is accommodated in recess 78a provided in the upper end of the oblique extension 79 of the crusher head gyrating shaft 80.

The obliquely inclined central axis 34d of shaft extension 79 meets the central vertical axis 34e of the main shaft section 80 at the focal point 81.

Shaft extension 79 comprises a taper portion 79a and a threaded end 79b. An adapter sleeve 82 (Figs. 1 and 3) is fitted on the taper portion 79a. The axis of the bore of sleeve 82 coincides with the axis 34d of shaft extension 79. The axis of the outer diameter of sleeve 82 is indicated at 44' and is obliquely inclined with respect to the axis 34d, the two axes meeting at the aforesaid focal point 81 which is located on the vertical axis 34e of shaft section 80 and which also constitutes the centre of curvature of the spherical surfaces 43 and 44. Sleeve 82 is turnable to various adjusted positions about taper portion 79a of shaft extension 79 and is secured in adjusted position by a pin 84 which is fixed in a portion of the shaft so that it may be selectively engaged in notches 85 provided in the lower end of said sleeve. Shims 86 are interposed between the upper end of sleeve 82 and the cylindrical extension 87 of a nut 88 which is fitted on the threaded end 79b of shaft extension 80. Nut 88 is formed with a spherical seat 89 and is locked in place by a locking wire 88a. As shown more clearly in Fig. 12 wire 88a is seated in nut groove 88b and has a bent end 88c extending inwardly through one of the radial openings 88d. The bent end 88c (see Figs. 12 and 13) is received in one of a series of notches 88e provided in the threaded shaft portion 79b. The upper end of the adapter sleeve on which the shims 86 bear is constituted by an annular face concentric with axis 34d.

Shaft extension 79 is journaled in the head carrier 63 by anti-friction bearing 92. The outer cone 93 of bearing 92 is force fitted in the cylindrical portion 94 of the head carrier 63 and is supported on the flat top surface 65 of liner 53. The inner cone 93a of bearing 92 is slip fitted on the adapter sleeve 82 so that sufficient pressure is exerted against the inner diameter of the cone when sleeve 82 is forced down the taper shaft portion 79a by pressure applied by nut 88.

The cylindrical extension 87 of nut 88 is encircled by a washer 95 provided with a spherical surface 96 (Figs. 1, 3 and 4) in matching contact with the spherical seat 89. The outer diameter of washer 95 is concentric with axis 44' while the lower face of said washer lies on a plane perpendicular to said axis and is in normal contact with the thrust face 93' of cone 93a (Fig. 4). The bore of washer 95 is concentric with the axis 34d of the obliquely inclined shaft extension 79. A pin 97 is rigidly fixed in washer 95 and is used to locate the washer circumferentially by being inserted in one of a series of threaded holes 98 formed in the upper end of adapter sleeve 82, said holes 98 being also adapted to receive threaded tools employed in with-

drawing the sleeve 82 from its wedging engagement with the taper shaft portion 80. Threaded holes 98' are also provided in head carrier 63 to facilitate dismantling of the force fit between the head carrier and the cone 93 as well as the force fit between the head carrier and the liner 53.

The lower portion of shaft section 80 is slidably fitted in bevel gear hub 10 and is positively rotated with said hub by means of the key 99. That portion of shaft section 80 which lies between the oblique shaft extension 79 and the upper end of hub 10 is centered in sphere head 40 by means of an anti-friction bearing 100 (Figs. 1 and 3). The outer cone 101 of bearing 100 is force fitted in a cylindrical portion 102 of sphere head 40 and bears against a flange 103 overhanging said cylindrical portion. The inner cone 104 of bearing 100 is force fitted on shaft section 80 and bears against the shaft flange 105.

The gyratory head shaft, comprising main shaft section 80 and oblique extension 79, is provided with a full length oil passage 107 through which some of the oil pumped to the previously mentioned oil passage 35 in cover 14 is forced over the upper end of the shaft to provide for the lubrication necessary for the shaft bearings 92 and 100 and the hub bearing 12 and 11. The upper end of oil passage 107 is partially blocked by a plug 108 (Fig. 6) provided with a restricted orifice 109.

A bull ring 110 is supported on and definitely located by the frame 4. The contacting surfaces of the bull ring and frame are carefully formed to ensure maximum efficiency when the crusher is in operation. In this connection it will be noted that the bull ring contacting surface of frame 4 is contoured so that it comprises a horizontal surface 111 and a radial curve 112 merging with a tangential projection 113 forming an inverted frustum of cone having an inclined angle of approximately 60 degrees. The horizontal surface 111 intersects a point on the curve 112 about 20 degrees from the vertical. The frame engaging surface of the bull ring is formed with a radial curve 114 matching the radial curve 112 and with a tangential projection 115 matching the tangential projection 113. The curve 114 of the bull ring merges with a horizontal tangential projection 116 which is normally spaced above the horizontal surface 111.

The bull ring 110 is preferably made of steel and must be of very strong construction. As indicated by dotted lines 118, it is mainly a frustum of cone form having upper and lower accurately bored cylindrical bore sections 119 and 120. Freely fitted in the bull ring is the cylindrical portion 121 of a mantle carrier 122. This cylindrical portion of the mantle carrier is threaded at its outer periphery so as to leave smooth full diameter band portions 123 and 124 above and below the threaded portion 125. The lower band portion 124 is provided with an annular groove 126 in which a suitable form of grease packing 127 is held so that said packing makes wiping contact with the lower cylindrical bore section 120 of the bull ring.

Four threaded segments 129 are arranged in the bull ring for threaded engagement with the threaded portion 125 of the mantle carrier. Each segment 129 is provided with a machined horizontal bottom surface 130 and is accurately bevelled as indicated at 131 to match the engaging bevelled surface 132 of the bull ring. The

segments 129 are supported by four clamps 133 disposed in contact with the bottom surfaces 130, each clamp having two threaded boss extensions 134 to provide ample threaded engagement with heavy cap screws 135 extending downwardly through boss extensions 136 of the bull ring. The force exerted by the head of each cap screw 135 is imposed against metal washer 137 and rubber canvas washer 138 supported by one of the boss extensions 136.

The bull ring is also provided with a boss 139a having a bore 139b in which a pinion shaft 139 is slidably fitted. A pinion 140 is fitted on the upper portion of said shaft and rests on boss 139a. A bushing 141 is fitted in pinion 140 to provide a bearing fit between the pinion and the pinion shaft. Pinion 140 is provided with a sleeve extension 142 having a top threaded opening 143 into which a plug 144 is screwed. When this plug is removed an eye bolt may be screwed into the threaded hole 145 at the upper end of shaft 139 to remove shaft 139 without disturbing the pinion.

The mantle carrier 122 is provided with a hopper forming portion 147 and with a cylindrical portion 148 extending upwardly from the hopper portion. The cylindrical portion 148 is provided with a machined surface 149 which engages and supports the machined bottom surface 150 of a cover ring 151 provided with depending inner and outer side flanges 152 and 153. The inner flange 153 of the cover ring is provided with a machined surface 154 in sliding contact with a machined surface 155 provided at the inner side of the cylindrical cover supporting portion 142. The outer flange 153 of the cover ring is also provided with a machined surface 156 in sliding contact with a machined surface 157 provided at the outer side of a collar 158 extending upwardly from an adjusting ring 159. The adjusting ring is supported on the top of the bull ring and is provided around its outer periphery with teeth 160 for engagement with the teeth of pinion 140. The adjusting ring is also provided with a depending flange 161 by means of which it is axially positioned on the bull ring, the contacting surfaces of the flange and bull ring being suitably lubricated. The top surface of the adjusting ring collar 158 is also machined since this surface contacts the cover ring surface 150 in certain adjusted positions of the mantle.

The bull ring is retained in position by a plurality of retaining bolts 163 extending downwardly through the bull ring bosses 164 and the frame flange 165. The head of each bolt 163 is formed with a spherically curved surface 166 disposed in contact with the spherically curved top surfaces 167 of a bronze washer 168 supported on one of the bull ring bosses 164. Each bolt is also encircled by a spring 169 which is interposed between the frame flange 165 and a washer 170, the latter being supported on the bolt by the nut 171. The springs 169 provide sufficient resistance to movement of the bull ring under normal conditions but yield to permit movement of the bull ring when uncrushable material is fed into the machine between the conical crushing head 74 and the conical mantle 171.

The mantle 171 is positioned within the mantle carrier by the sloping mantle surfaces 172 and the matching surface 173 of the mantle carrier and is retained in place by the mantle lugs 174 and the U-bolt 175. As here shown the bight portion of each bolt 175 is engaged beneath one

of the mantle lugs 174 while the arms of the bolts extend upwardly through openings in the mantle carrier and are fitted with nuts 176 which bear against an underlying washer assembly supported in the mantle carrier, said assembly comprising a resilient rubber-canvas washer 177 confined between upper and lower metal plates 178.

When the crusher is in operation, the counter-shaft 24 should be rotated in a direction opposite to the thread of the head fastening screw 75 in order to prevent loosening of the latter. Thus, when screw 75 is a right hand thread the countershaft 24 is rotated in an anti-clockwise direction thereby causing head shaft 80 to rotate in a clockwise direction when viewed in plan. Since adapter sleeve 82 is locked in place on oblique shaft extensions 79 by the pin 84, it follows that the axis 44' of the outer periphery of said sleeve will be caused to gyrate in response to the rotation of shaft 80, said axis describing an imaginary cone having its apex at the focal point 81 which is the focus of all gyrating motion. The roller bearing 92 is thus actuated to cause head liner 53 and head carrier 68 to oscillate on the spherical load bearing surface 44, the spherical surface 72a of the skirt portion 72 of the head carrier being also caused to move adjacent the spherical surface 43. Attention is called here to the wedging action of the crushing head 74 during its oscillation on spherical surface 44. As viewed in Fig. 1, the crushing surface 61' of head 74 comprises a straight conical upper portion C which is tangent to the curved lower portion V. It will also be seen that the inclination of the straight conical crushing surface C of head 74 with reference to spherical surface 44 is such that head 74 functions as a wedge, the wedging action of which varies with the position of the rock being crushed and increases, in effect, toward the discharge zone. The general disposition of the mechanism effecting this wedging action feature governs the selection of the cone angle of the head. It will also be apparent that the force behind the wedging action of the crushing surface C during its approach toward the crushing surface 78' of mantle 171, is mainly applied by the anti-friction bearing 92.

As hereinbefore mentioned, the principal object of this invention is to develop mechanical motion that will impose on the material to be crushed, the secondary forces of shear, torsion, and bending; it is therefore of great importance at this stage of my specification to carefully consider the action of rock reduction in this machine. Consider therefore the crusher under normal feed and operation when the rock contacting area is much greater at the discharge because of the even distribution near the discharge, and there being fifty per cent of the head making an approach toward the mantle. Then, the even distribution of the aggregate being sized at the discharge zone, acts to hold the freely rotatable crushing head 74 opposite the area of pressure on the mantle 171. It must be appreciated that this holding force is enormous (the actual machine from which these patent drawings are made had a head thirty inches diameter) and plays an important part in the fast reduction of large ore entering the crushing zone and such reduction is described herewith. When a large rock drops to its position in the crushing space S and head 74 approaches it, then it is obvious that the surface of the head does not make normal approach to the mantle surface but does move radially about focus 81. This is a differential

motion as respects the two surfaces of the head and mantle and which we herein term "vertical differentiation" and differs from direct impact. This vertical differentiation is mechanical and positive. The complete stroke from maximum to minimum is performed in 180 degrees of head shaft rotation, it is therefore at once apparent that the obliquity of axis 44' (which is here 3½ degrees) moves through an angle of 7 degrees about the focus 81. It must be kept in mind that the lower part of the head is rigidly held against rotation by the aggregate between the two crushing elements near the discharge zone, and it is because of this fact that that portion of the head near the intake must move to accommodate this oblique motion; thus, when viewed in the horizontal plane of the drawing, a point on the upper part of the head at the widest intake opening, viz., a point *a* would not move toward a point *b* on the mantle on the plane of the paper of the drawing, but the point *a* would have to move toward the observer to accommodate the motion caused by the oblique axis 44'. This is again a differential motion respecting the two surfaces of the head 74 and mantle 171 and varies in this instance from zero at the discharge zone to maximum at the intake zone. We herein term this motion a "horizontal differentiation."

To further elucidate this motion, let it here be considered that the crusher is running and empty and one large rock enters the intake and is nipped at the point *a* between the crushing elements. Here the aforesaid "vertical differentiation" is still effective on the rock because it is mechanical and positive, but the point *a* on the head 74 would move on the plane of the paper of the drawing toward the point *b* on the mantle 171 because such is now the center of maximum pressure and consequently the lower portion of the head 74 will move to accommodate the motion caused by the oblique axis. In this case there is no "horizontal differentiation" imposed upon the rock being crushed, the discharge zone being empty, and therefore void of rock pressure against the mantle 171, the head is free to move on its axis 44' and thus to make a partial rotation about the center of pressure of the solitary rock being crushed. The extra pressure and energy to break down a large rock under the last mentioned conditions is easily detectable by the measure of shock present in the machine when these circumstances obtain.

The "partial rotation" above mentioned is always present as it is mechanical and therefore positive, and is generally combined with both the horizontal and vertical differentiation aforesaid and produces torsion within the rock being crushed.

The bending stress above referred to is the eccentric loading imposed upon the rock because the approaching surface of the head 74 to the mantle 171 continually changes its alignment thereto. This is easily detectable in slow motion operation.

It is obvious that the condition herein described would be theoretically true regardless of the position of the focal point 81, the amount of differentiation varying with the position of the vertical axis 34e. It is therefore of importance to know if such focus be arbitrarily placed or if such be of general approximate location.

As hereinbefore stated, one of the objects of the invention is to produce a rock crusher that will perform a far greater reduction ratio than

is at present known to the art. To this end the crusher is designed so that the relationship between the position of the focal point 81, the amount of obliquity of the gyrating axis 44' and the contour and cone angles of the crushing members 74 and 171 is such that the point on the crushing head which makes the closest approach to the mantle during a crushing stroke does so with a downward component of motion which is not less than five times and not greater than seven times the component of motion in the direction of the mantle. In other words, the ratio between the vertical and horizontal distances travelled by said point in making its closest approach to the mantle during a crushing stroke should be as represented by the following formula:

$$\frac{X}{Y} = Z$$

where *X* (Figs. 1 and 14) represents the vertical distance traversed by that point *P* on the work face of the crushing head which, during a crushing stroke, makes the closest approach to the opposing work face of the mantle; *Y* represents the distance through which said point *P* moves in the direction of the opposing work face of the mantle during the said crushing stroke; and where the value of *Z* is not less than 5 and not greater than 7.

Fig. 14 is a diagram illustrating one method of designing a crusher so that the relationship between the position of the focal point 81, the amount of obliquity (OB) of the gyrating axis 44' and the contours and cone angles of the crushing members 74 and 171 is such that the point *P* on the crushing head work face which makes the closest approach to the mantle during a crushing stroke does so in such a way that the ratio between the vertical and horizontal distances traversed by said point is in accordance with the above mentioned formula. The dotted lines in Fig. 14 indicate the position assumed by the crushing head 74 when it is rotated 180° from the position indicated by full lines.

In the layout illustrated in Fig. 14 the angle of "nip" is indicated at *N* and is intended to represent an angle of 16° at mean obliquity setting (2½°) of the axis 44'. The obliquity of the axis 44' may be varied from a minimum obliquity of 1½° to a maximum obliquity of 3½° by appropriate adjustment of the previously mentioned adapter sleeve 82. The included angle *M* of the mantle 171 is 54° and the included angle *H* of the crushing head 74 is 80°.

The crushing surface 61' of the crushing head 74 comprises an upper portion *C* of straight cone contour and a lower curved portion *V* which is involute to an imaginary circular evolute *D* whose centre coincides with the focal point 81. The involute *V* is of a greater degree of curvature in its lower portion than in its upper portion. The point *P* is located on the curved portion *V* so that, when said point reaches its position of closest approach to the mantle crushing surface 18', it lies on a normal *R*₁, the length of which is approximately six times the radius *R* of the evolute *D*. In this particular case the ratio of *R*₁ over *R* is equal to approximately 6 and the ratio between the vertical and horizontal distances travelled by the point *P* in making its closest approach to the mantle is represented by the formula

$$\frac{X}{Y} = 6$$

It will now be shown that, when the position of the focal point 31 is changed so that the ratio of R_1 over R equals some value other than 6, there will be a resulting change in the ratio between the vertical and horizontal distances traversed by the point P in making its closest approach to the mantle.

As an example, the location of the focal point 31 shown in Fig. 15 is such that the ratio of R_1 over R is assumed to equal 5. In this case the ratio between the vertical and horizontal distances traversed by the point P in making its closest approach to the mantle would be represented by the formula

$$\frac{X}{Y} = 4\frac{1}{2}$$

approximately. Similarly, the location of the focal point 31 shown in Fig. 16 is such that the ratio R_1 over R is assumed to equal 7 using the radius R for the circular evolute D. In this case the ratios between the vertical and horizontal distances traversed by the point P in making its closest approach to the mantle would be represented by the formula

$$\frac{X}{Y} = 8$$

As previously intimated, it is an important feature of this invention that the design of the crusher be such that value of Z in the formula

$$\frac{X}{Y} = Z$$

shall be not less than 5 and not greater than 7. In other words, if the point P in making its closest approach to the mantle travels through a vertical distance which is less than five times or greater than seven times the horizontal distance traversed by said point the efficiency of the pressing action is impaired as compared with the case where the ratio between the vertical and horizontal distances travelled by the point P in making its closest approach to the mantle is in accordance with the formula

$$\frac{X}{Y} = 5 \text{ to } 7$$

inclusive.

To further clarify this vital relationship an analogy (Fig. 17) may be used, to wit, a flat surface for the stationary and resisting work surface 18' while the moving member 74 is assumed to have a flat surface in one direction. In the other direction a flat surface portion C of surface 61' is inclined with respect to surface 18' or a parallel thereto, said inclination being approximately 10 degrees from surface 18'.

The curve V of surface 61' is involute to an evolute D whose radius R is approximately one sixth of the length of normal R_1 . The entire surface 61' moves about the evolute center 31, receding 6 degrees, thus the surface C oscillates between 10° to 16° from surface 18'.

As is well known, if rock material be placed between two surfaces making normal approach the one to the other, then an infinite amount of pressure cannot make those surfaces meet because the friction of the expanding crushed rock against its confining surfaces, prevents further expansion of the rock thus retained in the center of pressure. If, however, a differentiation of said surfaces be effected in proper proportion with the pressure applied, then such action may continue until the surfaces meet.

Referring therefore to Fig. 17 and which is analogous to the action of the crusher disclosed in this invention, it can be demonstrated that if when in the position of nearest approach surface 61d meets surface 18' and surface 61' is 10° from surface 18', that if these surfaces be resisted from movement except that member 74 may rotate about evolute center 31, and that surface 61' be receded 6 degrees, that average hardness dry rock be allowed to fall therebetween, sufficient power can now be applied to rotate member 74 as will cause surface 61d to meet surface 18' due to the vital ratio of differentiation hereinbefore mentioned.

Reverting to Figs. 14 to 17 inclusive, it is pointed out that the normal R' of involute curve V may be substituted by a radius to form an arc in place of the involute curve V. The maximum difference in the range used (less than one seventieth of a circle) is less than one half of one per cent. Thus the substitution of an arc for the involute curve V is a feasible substitution within the scope of this invention.

As is well known to the crushing art, different rocks and ores and other crushable materials vary widely in their friability and structure and the same results would not be obtained for each kind in a crusher of set characteristics. I have therefore incorporated into my machine novel means for varying the obliquity of the gyrating axis, and at the same time providing a unique and efficient method of applying the upper roller bearing cone 93a, and this can be easily appreciated as a vital point in the general assembly seeing all resistance to prime motion must be resisted by this bearing.

Referring to Fig. 1, the adapter sleeve 82 engages the taper shaft end 79a, being a jamming taper of 9 degrees. The adapter 82 is a slip fit in bearing cone 93a, but with pressure applied by nut 83 forcing sleeve down taper 79a the proper amount of interference may be imposed against the cone bore to meet the manufacturer's requirements for this type of service.

In assembling, the bearing cone 93 is placed on the surface 65 of head liner 53, the adapter 82 and cone 93a are placed into position, care being taken to see that pin 84 engages the desired notch 85 for the amount of obliquity required; shims 86 are then placed on annular face 82', next spherical washer 95 is positioned and nut 88 screwed down with a predetermined degree of torque or effort, such effort being principally imposed against taper 79a through sleeve 82 and shims 86.

With shaft 89 retained in its uppermost position by some exterior lifting force, and by the use of a suitable gauge, the amount of clearance between cone 93 and flat surface 65 may be determined. If the clearance here is too great, then a shim 86 must be removed and nut 88 replaced. It is important here to note the relationship existing between the nut 88, the washer 95, the cone 93a and the adapter sleeve 82.

It is important to bear in mind at this stage that the adapter sleeve 82 was forced down the gripping taper 79a and has imposed an interference fit on the bore of cone 93a and which fit still exists even though the nut 88 is removed. The nut 88 is now replaced and when the spherical face 89, the flat face of washer 95, and the cone face meet, there will exist between the upper end of adapter 82 and the extension 87 of nut 88, a space equal to the thickness of the shim removed from shims 86.

The effort now applied by the nut 88 will be first effective in sliding the cone 93a along the axis 44' of adapter 82 to be followed by sufficient effort to maintain a rigid assembly. The above procedure can be followed until the desired adjustment is obtained. The precise clearance here required is ascertained from a formula furnished by the bearing manufacturers in conjunction with the interference fit of the cone 93 in the head carrier 68.

To vary the obliquity of the gyrating axis 44' as respects the vertical axis 34e, the obliquity of the axes 34d and 44' of the adapter sleeve 82 is used to increase or decrease the set obliquity of the head shaft axes 34d and 34e. It is convenient to have this set obliquity of the head shaft 80 two and one-half degrees, and the obliquity of the axes of the adapter 82 one degree. As shown in Fig. 1, the obliquity of one degree of the adapter 82 is added to the obliquity of 2½ degrees of the axis 34d, thus making a total obliquity of 3½ degrees. It is obvious that by rotating the adapter 82 180 degrees, the one degree of the adapter obliquity would be subtracted from the shaft obliquity of 2½ degrees, thus making the effective obliquity of the gyrating axis 44' one and one-half degrees. Notches 85 of which there are five, as shown in Fig. 8, would give increments of one-half degree from a minimum of 1½ degrees to a maximum of 3½ degrees obliquity of the gyrating axis 44'. To effect this change of adjustment, it is only necessary to remove the head carrier 68, remove the nut 88, withdraw the adapter 82 sufficiently to rotate said sleeve to the required adjustment and then to tighten nut 88 to its original position, suitable indicating figures (not shown) being stamped on top surfaces of the nut and head shaft for this precise purpose.

The exclusion of dust from the means of adjustment in gyratory crushers usually involves the use of auxiliary component parts such as rings, channels, dust shields, etc., with unsatisfactory results whereby dust penetrates into the lubricated machined parts. In my invention this disadvantage is overcome by forming the bull ring 110 with two cylindrical areas 119 and 120, both being bored to one diameter with the necessary beveled edges, so that greased packing 127 may conveniently enter when required to do so by the assembly of the mantle carrier 122 into the bull ring 110. It will be noted that the annular band portions 123 and 124 of the mantle carrier 122 are of one diameter and are machined for free fit within the bull ring 110. Due to this construction it is entirely unnecessary to provide auxiliary pieces to hold the packing 127 or to provide a cylindrical shield as a seal medium, the bull ring 110 offering a rigid, integral cylindrical sealing surface 120.

The satisfactory seal arrangement above mentioned is made possible by the novel arrangement of the movable threaded wedge segments 129 and which are adapted to be closed in on the threaded portion 125 of mantle carrier 122. This movement of the threaded wedge segments 129 is accomplished in the following manner: Before entering the mantle carrier 122 into the bull ring 110, the cap screws 135 are slackened to permit the clamps 133 to drop to the chain line position shown in Fig. 1, thus permitting the wedge segments 129 to likewise lower accordingly. Due to the cone angle of the surfaces 131 and 132 wedge segments 129 may now recede radially sufficiently to clear the mantle carrier 122, which is now

lowered to its approximate position. Turning cap screws 135 will cause the clamps 133 to rise, thus raising threaded wedge segments 129, said segments will therefore be confined by contact with the threaded portion 125 of mantle carrier 122 on the inside; by contact with the slope of the conical surface 131 on the outside, and by the clamps 133 on the underside.

It should be noted that the upward crushing forces imposed on the mantle 171 assist to maintain intimate contact between the bull ring 110 and the mantle carrier 122, due to the wedging action of wedge segments 129.

When it is necessary to make an adjustment 15 of the crusher space S for product size, the cap screws 135 are slackened about one-half turn each with a suitable wrench and then, with the same wrench, which fits the square section on the top portion of pinions sleeve 142, the turning of said pinion 140 will rotate the adjusting ring 159, which, in turn, will rotate the mantle carrier 122 by means of lug 159a in groove 122a. The coarse pitch thread 125 will quickly bring the mantle carrier assembly to the desired position, when it is only necessary to tighten the cap screws 135. This has proved a very rigid locking arrangement in service. The adjustment herein described can be carried out by two operators if desired, by providing pinions 140 at opposite sides of the bull ring 110.

In gyratory crushers where all the operating mechanism is under the crushing zone S, the importance of separating the dust laden air without, from the load bearing lubricated surfaces within, is at once apparent and cannot be overstressed. This important function is effectually solved in the case of my invention by placing the oil seal ring 48 in shrink fit about the parallel cylindrical portion 46. It will be observed that 30 when the bottom edge of head liner 53 is in its uppermost position, it is still well below the top edge of the oil seal ring 48 and at a distance from it, thus, oil adhering to the said bottom edge of head liner 53, and oscillating at 400 R. P. M. in 35 an arc about the focus 81, is trapped by the oil seal ring 48 and completely retained within its proper limits.

The spherical surface 72a provided adjacent the lower edge of the skirt portion 72 of head carrier 68 is positioned closely adjacent but not in actual contact with the spherical surface 43 of sphere head 40. These surfaces 72a and 43 are dry and without lubricant and are effective to prevent the passage of dust laden air from entering the annular space 73. This arrangement acts as a "breather" or vent to the otherwise air tight chamber containing the lubricated working parts of the machine, the expanding or contracting air within the confined chamber having free passage through holes 50 and thence over the oil seal ring 48 and through the vent space at the spherical area 43. Thus a triple purpose is served by this novel arrangement, to wit: an oil seal, a dust seal and as a vent, each of which functions are effectually performed in service.

As previously stated, the excess oil passing relief valve 60 serves to lubricate the pump drive spiral gear 32 and the countershaft bearings 26 and 27, said oil draining off into sump 37 in bottom cover 14 through outlet 38, thence to filtering tank (not shown).

What I claim is:

1. A gyratory crusher of the cone and mantle type comprising cone and mantle elements of substantially frusto-conical form, said elements

being relatively inclined so that their central axes meet at a focal point located below a crushing zone formed by and between their opposing crushing surfaces, and means for gyrating the cone element about said focal point, said means comprising a driven shaft including a main shaft section and an obliquely inclined shaft extension, the main shaft section being journalled so that its central axis coincides with the central axis of the mantle element and meets the central axis of the inclined shaft extension at said focal point, said inclined shaft extension being journalled in the cone element by means comprising an adapter sleeve fitted on said shaft extension and an antifriction bearing interposed between a portion of the cone element and said adapter sleeve, the axis of the bore of said sleeve coinciding with the axis of said shaft extension and being obliquely inclined with respect to the axis of the outer periphery of the sleeve, the last mentioned axis coinciding with the central axis of the cone element, said sleeve being adjustable about said shaft extension and means for securing the sleeve in adjusted position.

2. A gyratory crusher as set forth in claim 1 in which the means for securing the adapter sleeve in adjusted position comprises a pin fixed to the shaft and projecting into one of a series of pin receiving recesses formed in the sleeve.

3. A gyratory crusher as set forth in claim 1 in which the shaft extension and the bore of the adapter sleeve are tapered to provide a jamming fit therebetween.

4. A gyratory crusher as set forth in claim 1 including a nut threaded on the end of the shaft extension to exert pressure against the adjacent upper end of the adapter sleeve, and a pin fixed to the main section of the shaft and projecting into one of a series of pin receiving recesses provided in the lower end of the adapter sleeve.

5. A gyratory crusher as set forth in claim 1 in which the shaft extension and the bore of the sleeve are tapered to provide a jamming fit therebetween and in which the sleeve is forced into tight jamming engagement with the tapered shaft extension by means of a pressure applying nut threaded on the upper end of said extension and bearing against the upper end of the sleeve.

6. A gyratory crusher as set forth in claim 1 including an inner race member encircling said sleeve and forming part of said anti-friction bearing a pressure applying nut threaded on the upper end of said shaft extension, shims interposed between a lower portion of said nut and the adjacent upper end of the adapter sleeve, and a washer interposed between another portion of the nut and the upper end of said inner race member, said washer and nut being provided with spherically curved bearing surfaces curved about a centre lying below said surfaces.

7. A gyratory crusher of the cone and mantle type comprising a frame, a mantle element, means mounting said mantle element on said frame so that the central axis of the mantle element is vertical, a cone element arranged within said mantle element and constituting a crushing head, a support on which the cone element is mounted in a tilted position so that the central axes of the mantle and cone elements are relatively inclined to meet at a focal point located below a crushing zone formed by and between the opposing crushing surfaces of said elements, a cone driving shaft including a main section and an obliquely inclined shaft extension, the main shaft section being journalled so that its central

axis coincides with the central axis of the mantle element and meets the central axis of the inclined shaft extension at said focal point, and means for journalling said inclined shaft extension in the cone element said means including a tilt-adjusting element which is adjustable to vary the extent to which the cone element is tilted.

8. A gyratory crusher of the cone and mantle type comprising a frame, a mantle element, means mounting said mantle element on said frame so that the central axis of the mantle element is vertical, a cone element arranged within said mantle element and constituting a crushing head, a support on which the cone element is mounted in a tilted position so that the central axes of the mantle and cone elements are relatively inclined to meet at a focal point located below a crushing zone formed by and between the opposing crushing surfaces of said elements, a cone driving shaft including a main section and an obliquely inclined shaft extension, the main shaft section being journalled so that its central axis coincides with the central axis of the mantle element and meets the central axis of the inclined shaft extension at said focal point, and means for journalling said inclined shaft extension in the cone element said means comprising an adapter sleeve fitted on said shaft extension and a bearing assembly interposed between a portion of the cone element and said adapter sleeve, the axis of the bore of said sleeve coinciding with the axis of said shaft extension and being obliquely inclined with respect to the axis of the outer periphery of the sleeve, the last mentioned axis coinciding with the central axis of the cone element, said sleeve being adjustable about said shaft extension and means for securing the sleeve in adjusted position.

9. A gyratory crusher of the cone and mantle type comprising cone and mantle elements of substantially frusto-conical form, said elements being relatively inclined so that their central axes meet at a focal point located below the crushing zone formed by and between their opposing crushing surfaces, and means for gyrating the cone element about said focal point so that, at each crushing stroke, the portion of the active crushing surface of the cone element which makes the closest approach to the opposing crushing surface of the mantle does so with a substantial downward component of motion, said crusher being further characterized in that the crushing surface of the mantle, as viewed in vertical cross section, is of straight cone contour while the opposing crushing surface of the cone element, as viewed in vertical cross section, comprises an upper portion of straight cone contour and a lower curved portion which is involute to an imaginary circular evolute whose centre coincides with said focal point and whose radius is approximately one-sixth the length of its normal which is perpendicular to the crushing surface of the mantle, said straight cone contour portion of the cone element being tangent to said involute curved portion and the latter being tangent to either the mantle crushing surface or a parallel thereto and being also of a greater degree of curvature in its lower portion than in its upper portion.

10. A gyratory crusher of the cone and mantle type comprising cone and mantle elements of substantially frusto-conical form, said elements being relatively inclined so that their central axes meet at a focal point located below the crushing zone formed by and between their opposing crush-

ing surfaces, and means for gyrating the cone element about said focal point so that, at each crushing stroke, the portion of the active crushing surface of the cone element which makes the closest approach to the opposing crushing surface of the mantle does so with a substantial downward component of motion, said crusher being further characterized in that the crushing surface of the mantle, as viewed in vertical cross section, is of straight cone contour while the opposing crushing surface of the cone element, as viewed in vertical cross section, comprises an upper portion of straight cone contour merging with a lower portion which is curved so that, when said lower portion is making its closest approach to the mantle, the point on the arc of curvature which is nearest the mantle is located on a radius which is perpendicular to the crushing surface of the mantle and substantially tangential to an imaginary circle whose centre coincides with said focal point and whose radius is approximately one-sixth the length of the first mentioned radius.

11. A gyratory crusher of the cone and mantle type comprising a frame, a mantle element of 25

substantially frusto-conical form mounted on said frame so that its central axis is vertical, a gyratory cone element of substantially frusto-conical form arranged within said mantle element, said frame and cone elements being provided with spherically curved bearing surfaces in contact with each other said cone element being tilted so that its central axis meets the central axis of the mantle element at a focal point which constitutes the center of curvature of said spherically curved surfaces and is located below the crushing zone formed by and between the opposing crushing surfaces of said cone and mantle elements, one of said spherically curved surfaces having an annular groove formed thereon, the side walls of the groove being curved at the mouth of the groove so that oil supplied under pressure to said groove is distributed between the spherically curved surfaces on the oil film feed thrust principle, means for conducting surplus oil away from said groove, said last mentioned means including an oil pressure regulating valve, and means for gyrating said cone element about said focal point.

RAYMOND E. BROWNING.
